Application October 25, 1945, Serial No. 624,360

37 Claims. (Cl. 250—27.5)

1

My invention relates to electron discharge devices, more particularly to amplifier tubes useful at very high frequencies and delivering large amounts of power.

The provision of a tube which will operate at very high frequencies and deliver large amounts of continuous power with reasonable band width and power gains presents serious problems incapable of solution with conventional tube designs.

The dissipation of heat, which is one of the most serious problems and which must be accomplished to protect seals and electrodes and to prevent undesired electron emission, requires structures which with conventional design adversely affect the electrical characteristics of the device in the way of increased inductances and capacitances and increased electron transit times. This limits operation at high frequencies, particularly when the desired band width is that required for television. Heat causes expansion and contraction of the tube elements, thus affecting spacings and alignments and operating stability. The need to dissipate heat from all electrodes and elements introduces further cooling problems since for high frequency operation small structures and close spacings are a prerequisite.

High frequency operation on the other hand requires small electrodes and leads and close spacing to reduce interelectrode and lead capacitance and inductance and to limit the transit time of the electrons between the electrodes to such value that the transit time does not become an appreciable percentage of the period of oscillation. That is, the transit angle must be small. However, close spacing increases interelectrode capacitances and consequently the electrode area must be decreased and thus for high power output cooling becomes difficult with such compact structures.

At high frequencies stable and efficient operation can be had only by properly isolating the input and output circuits and electrodes.

To obtain high power outputs at reasonable anode voltages and to encourage decreased transit angles, high current densities are required. This requires proper field and electrode configurations.

Further, when the transit times for all simultaneously emitted electrons cannot be made small, substantially equal transit times for electrons simultaneously emitted from various parts of the cathode surface are desired so that the upper frequency limit of operation at which normal electronic efficiencies may be obtained is not decreased. In addition the current must be formed

2

into beams to reduce electron absorption by the control and screen grids, which absorption by the grids would increase grid heating and undesired grid emission and decrease the amount of useable current to the anodes. Conventional beam forming electrodes, however, complicate tube structure, introduce undesired capacitance and inductance and aggravate the cooling problems.

In push-pull operation at high frequencies neutralization to prevent spurious oscillation is a problem since short leads are required to minimize phase shift. When two tubes of the tetrode type are operated side by side in push-pull operation the screen grid structures, leads and external screen connections utilized become an oscillating circuit and impose undesired resonant conditions on the tubes. Further small differences in tube structures result in unbalanced push-pull amplifier circuits.

20 The conventional methods of cooling an anode when the tube is designed for high power output at high frequencies are not always effective because of the inability to dissipate large amounts of generated heat rapidly from small closely spaced electrodes.

The manufacture of a tube of the type described is also complicated by the close spacings and accurate alignments required.

It is, therefore, a principal object of my invention to provide an improved electron discharge device particularly useful as an amplifier and delivering large amounts of power at ultra high frequencies.

Another object of my invention is to provide such a device, particularly suitable as a push-pull amplifier, having substantially complete electrical stability and freedom from oscillation.

A further object of my invention is to provide such a device having a small average grid current, thereby permitting operation as a grid modulated power amplifier at 300 megacycles and higher.

An object of my invention is to provide a device of the kind described having very high cathode-electron emission densities.

45 Another object of my invention is to provide a device of the kind described having very high cathode-electron emission densities which can be controlled with control grid currents of a small percentage of the anode current.

Still another object of my invention is to provide such a device having field and electrode configurations insuring small electron transit angles.

A further object of my invention is to provide 55 such a device having a beam forming cathode as-

sembly which minimizes electron absorption by the control and screen grids.

Another object of my invention is to provide an electron discharge device having small electrode structures, short leads and close spacings yet capable of large continuous power outputs at high frequencies and in which efficient cooling is obtained and in which interelectrode and lead capacitances and inductances are maintained at very low values.

A still further object of my invention is to provide novel and efficient cooling of all seals and electrodes thereby increasing the power output capacities of the small electrodes and leads essential for high frequency operation.

More specifically it is an object of my invention to provide an improved method and means for cooling the output electrode or anode.

Another object of my invention is to provide a device having precision parts which can be accurately and easily assembled and aligned and in which alignment and spacing are rigidly maintained during operation, thus minimizing change of electrical characteristics.

A still further object of my invention is to provide such a device suitable for push-pull operation and having an improved internal neutralizing means.

A further object of my invention is to provide an electron discharge device for push-pull operation in which balanced push-pull operation is insured.

Another more specific object of my invention is to provide an improved means for shielding the input and output circuits and electrodes from each other.

A further object of my invention is to provide means for fluid cooling of the cathode support, control and screen grids.

A still further object of my invention is to provide novel improved constructions of the cathode, control grid, screen grid and anode electrodes resulting in improved characteristics and efficiencies.

The novel features which I believe to be characteristic of my invention are set forth with particularity in the appended claims, but the invention itself will best be understood by reference to the following description taken in connection with the accompanying drawing in which Figure 1 is a schematic diagram of an electron discharge device employing the principles of my invention, Figures 2 to 6, inclusive, are schematic cross sectional diagrams of focusing arrangements which may be employed with my invention, Figure 7 is a sectional perspective showing the relative shapes and positions of the electrodes employed in my invention, Figure 8 is a side elevation, partially in section, of an electron discharge device employing my invention, Figure 9 is a section taken along the line 9-9 of Figure 8, Figure 10 is a longitudinal transverse section taken along the line 10-10 of Figure 8, Figure 11 is a partial transverse section taken along the line 11-11 of Figure 10, Figure 12 is an end elevation of Figure 8 with parts in section showing details of construction, and Figure 13 is an exploded perspective of the electrodes comprising the mount construction of the electron discharge device shown in Figures 8 to 12, inclusive.

Briefly, an electron discharge device made in accordance with my invention includes an evacuated envelope containing a mount assembly comprising two electron emitting cathodes, two first or control grids, two second or screen grids and

two anodes with neutralizing elements all combined and disposed to form an internally neutralized duplex tetrode. The neutralizing elements may be attached to either the grid or anode of one tetrode section and perform the function of neutralization by means of direct capacitance between the neutralizing element and the grid or anode of the other tetrode section when the tube is operated as a push-pull amplifier.

The schematic arrangement of such a tube is shown in Figure 1 in which the double cathode 13 has mounted on either side control grids 11-12, screen grids 13-14 and anodes 16-17, the neutralizing capacitances being indicated at 18 and 19 and the by-pass capacitance between the screen electrode and cathode being shown at 20, all the electrodes being mounted within a common envelope 21. The cathode is grounded to the envelope and the screen grids are combined to form a unitary screen grid structure. Shielding 22 is connected to the screen grid structure and shields the control grid circuits from the anode circuits.

In order to provide controlled beams having high current densities and to permit the close spacing of the control and screen grids, which is required for efficient high frequency-high power operation, the electric field and electrode configurations become important.

In the practice of my invention the electric field configuration at and near the cathode is of such form that the emitted electrons are focused to form a beam passing between the grid elements, the electric field configuration being obtained by means of fluted or planar focusing elements operating at a zero or negative potential with respect to the planar or fluted cathode elements.

A number of such arrangements are disclosed in Figures 2 to 6, inclusive, wherein C is the cathode and F the focusing elements. The dashed lines indicate the electron paths. The electric field near the electron emitting surface is such that the electrons leaving this surface are subjected to a force which has a component directed toward an axis through the center of the emitting surface and perpendicular to it, this force component being greatest in the region of the edges of the electron emitting strips. Such electric fields are produced by electrode configurations shown where the focusing electrodes F are at cathode potential or negative with respect to it. Any of these arrangements may be utilized with my invention.

However, I prefer to utilize the arrangement shown in perspective in Figure 7. In this arrangement the focusing electrode may be formed from a planar solid block 27 having a plurality of parallel grooves or slots 26 within which are received the flat strip or ribbon-like cathode filaments 25. Mounted above and in registry with the portions of the focusing electrode intermediate the slots 26 are the control grid rods 28 also preferably of rectangular or beveled rectangular cross sectional shape and registering with these rods 28 are the screen grid elements 29. The purpose of the concave surface 31 of the portions of the focusing electrode is to reduce the capacity between the control grid elements 28 and the focusing electrode elements of electrode 27. An anode 30 receives the electrons from filament cathode 25.

With the focusing elements formed and arranged as shown an adequate focusing electric

field is produced at or near the cathode surface without the electrodes themselves projecting appreciably in the direction of the anode, thus permitting control grids being placed in close proximity to the plane of the cathode which is desirable and essential for efficient high frequency operation and for insuring a reduction of transit time by reducing spacings.

The grid electrode elements of rectangular or beveled rectangular cross section, mounted with the widest face toward the cathode and focusing elements, provide effective control of the electron beam and act like thin elements with small electron absorption from the beam but nevertheless have a substantial cross section for conducting heat to the mounting pipe on which these elements are supported and for maintaining mechanical rigidity and stability. These electrode elements provide a smaller effective electrode spacing for comparable clearances when compared to more conventional or circular section elements. Tests with control grids utilizing such cross sectional areas show that increased beam current densities may be controlled with decreased grid currents.

The planar or concave electron emitting surfaces of the strip cathode elements function to provide substantially equal transit times for electrons simultaneously emitted from various parts of the cathode surface. Since electrons having substantially different transit times from the average, as may be encountered in conventional "squirrel-cage" structures, will necessarily have longer transit times, this effect tends to increase the upper frequency of operation at which normal electronic efficiencies may be obtained. These strip cathodes also deliver substantial electron emission current densities with a minimum of magnetic modulation of the electron trajectories and are superior to cathode elements of circular cross section in this respect.

Because of the increased electron current densities which may be utilized (in practice 3.5 amperes per square centimeter of cathode surface have been obtained and successfully utilized) and the decreased effective electrode spacings, the transit angle of grid controlled amplifier tubes made according to my invention is substantially decreased. It may be shown that, for parallel plane electrodes,

$$\theta = K \left(\frac{S}{J} \right)^{1/2}$$

where θ is the transit angle from cathode to grid plane, J is the electron beam current density and S is the effective spacing between cathode and grid, this being the region of interest for transit angle consideration for the operation of this invention. Since these field and electrode configurations permit increased electron current densities and decreased transit angles, new high frequency wide band power amplifier tubes are made possible, such tubes operating at 300 megacycles with 5 kilowatts output and a total band width in excess of 10 megacycles.

An electron discharge device made according to my invention and embodying the principles described above is shown in Figures 8 to 13, inclusive.

Essentially the cathode and focusing electrode assembly comprises liquid cooled metallic focusing and mounting blocks with a multi-filament U-shaped cathode encompassing and clamped to these blocks. The electron emitting surfaces of the cathode may be of pure metal, such as tanta-

lum, or may be oxide coated on a metal strip. The focusing elements are an integral part of the cathode mounting blocks. Briefly the cathode comprises an elongated U-shaped member including a plurality of electron emitting strips parallel to each other and received within parallel focusing grooves or slots on the cathode block.

Referring specifically to Figures 10, 11 and 13, the cathode and focusing electrode assembly comprises the focusing electrode blocks 35 and 36 insulated from each other by means of the mica separator or spacer 38 and provided with a plurality of parallel rectangular slots 37 into which the emitting elements of the cathode are positioned. These blocks are clamped together in the mount assembly by means of screws 35' and 36' insulated from one of the focusing blocks. These blocks are in turn supported by and clamped between the liquid-cooled header mounting blocks 39 and 40 insulated from each other by means of the mica spacer 41'. One block is provided with the extension 41 for clamping the assembly to the header in a manner to be described. The focusing blocks or elements are secured to the mounting blocks by means of the screws 42, 42'.

The cathode comprises a plurality of elongated U-shaped elements 47 secured at the ends of the legs by means of the elements 48, 48', the elements 47 lying in parallel planes. These emitting elements are received within the slots 37 of the focusing blocks and nested within the slots below a plane passing through the outer surfaces of the portions of the focusing block between the slots, the relationship being as clearly disclosed in Figure 7. As shown in Figure 11 the cathode and the cathode shields 50 and 51 are secured to the focusing block by means of screws 51' and 52' so that the clamped ends of the U-shaped cathode filaments are shielded against emission. A cathode shield 52 is secured to the end of the cathode focusing blocks to cover and prevent emission from the closed end of the U-shaped cathode filaments and another shield 53 is positioned at the bottom of the focusing elements to prevent the emission of stray electrons which would miss the anodes and bombard the glass envelope. It is evident that there is thus provided a unitary water-cooled cathode and focusing electrode assembly for providing a plurality of parallel beams directed from opposite surfaces of the planar structures.

The cathode and focusing structures described provide electronic, circuit and mechanical advantages that are of particular significance when these structures are incorporated in amplifier tubes. These structures provide and permit liquid cooling of the mounting, supporting and lead-in structure in a manner to be described and thereby reduce thermal expansion sufficiently to maintain the electrode alignment in normal operation substantially that introduced during assembly. The accurate alignment that can be obtained during assembly and maintained during normal operation along with the mechanical symmetry of the described structure makes possible a grid-to-cathode and grid-to-screen grid capacitance balance between two tetrode sections of the duplex tetrode amplifier tube together with small spacings and very low control grid and screen grid current pickup from the high density electron beams.

The cathode and focusing structure described provides a low impedance electrical connection 75 between the individual cathode and focusing ele-

ments of each tube section and between the two cathode and focusing sections of the duplex tube. Such low impedance is advantageous in ultra high frequency push-pull amplifiers.

The method of cathode mounting and the mounting structures make it possible to provide a screen grid-to-cathode bypass arrangement to be described, which is of low electrical impedance and has connections of extremely low inductance. In this arrangement an efficient and compact capacitor can be utilized because it can be mounted within the vacuum enclosure. Further, the structure with the focusing elements formed in the cathode block provides a low-resistance cooled metallic conductor as the focusing element which also acts to conduct most of the input grid charging currents induced during operation of the device.

The control grid structure is placed next adjacent the cathode and cathode focusing electrode assembly. The grid assembly is composed of a metallic tube or pipe sealed through and supported by a glass seal of the envelope and into which wires or slats are fixed with good thermal and electric contact, the slats being mounted transversely to the supporting pipe axis and functioning as the controlling elements. The element length is chosen relative to the element cross section so as to permit all of the power dissipated in the elements to be conducted to a coolant circulated in the supporting pipes. The mechanical mounting and positioning of the elements is obtained by means of holes or slots machined in the supporting pipe or in a metallic block or strip, which can be secured thereto. The neutralizer structure referred to above consists of metallic lugs fixed to the grid supporting tube and projecting through the screen grid enclosure.

Specifically, each control electrode comprises the tubular pipes 56 and 56' having slots for receiving the transverse parallel spaced control grid elements 55, 55' having elongated rectangular shaped transverse sections. Inner tubes 57, 57' serve to conduct a coolant into or out of the pipe 56, 56' serving as the grid element supports. To provide neutralizing elements, the pipes 56 are provided with L-shaped lugs 58 and 58', carrying the elements 59 and 59' which serve to provide capacitance coupling to the anodes to be described. Each of these grids is electrically insulated and separately supported by a seal through the tube header in a manner to be described.

The grid structure described above provides a sturdy mechanical support and accurate alignment and spacing of the elements that is maintained during normal operation of the device in which the grid is mounted. This is obtained by the effective cooling of the supporting tubes and the attached glass seal to be described, which eliminates misalignment of the electrodes by thermal expansion due to energy absorbed by the control grid elements or power dissipated in the supporting and lead-in pipe. This effective cooling of the supporting pipe provides a means for cooling the control grid elements and thus prevents excessive electron emission from the elements.

The neutralizer arrangement and structure permits a minimum length and consequently minimizes the phase shift due to neutralizer lead length. This arrangement is especially adaptable to duplex tetrode amplifier tubes made according to my invention.

Surrounding the cathode assembly and control grids is a screen grid which is fluid cooled

and of unitary construction. This unitary structure is in the form of a box-like frame having open sides and having grid elements spaced and aligned by means of slots machined in the metallic frame, the elements being silver soldered or otherwise fixed to the frame with good thermal and electric contact.

Still referring to Figures 10, 11 and 13, this unitary screen grid assembly comprises a pair of more or less U-shaped members 60 and 61. The U-shaped members 60 and 61 are secured to the end block members 44 and 45 to form a box-like structure open at the sides, the screen grid elements being positioned within these open spaces. Members 60 and 61 are provided on the outside and along the inner edges of the legs with bevelled surfaces 62, 63, 64 and 65, these U-shaped members 60 and 61 being provided with inwardly extending portions 66, 67, 68 and 69 provided with slots in which the screen grid rod-like elements 71 and 72 and 71' and 72' are positioned and fixed to the U-shaped members. The positioning of the elements on the inside face of the U-shaped members 60 and 61 provide a pocket in the outside sides of the screen grid to receive the anodes to be described. As shown in Figures 10 and 11, these screen grids are secured to the members 74 and 75 by means of the screw members such as 74' and 75'. These members 74 and 75 are in turn clamped to the cathode supporting blocks but insulated therefrom by means of the insulating spacers 76 and 77 preferably of mica, the bolts 79 being insulated from the elements which are clamped by means of the insulating spacers 79'. The mica spacers position the attaching blocks 74 and 75 in capacity relationship with the cathode cooling blocks so that radio frequency current from the screen grid may be bypassed to ground through one of the supporting blocks. The U-shaped members 60 and 61 are provided with apertures 60' and 61' through which the lugs 58 and 58' supporting the neutralizing elements 59 and 59' extend. It will thus be observed that the cathode and focusing electrode and the unitary screen grid are supported as a rigid compact structure from the header member.

Because of the arrangement described, the screen grid and mounting structures provide circuit, thermal and mechanical advantages. Several circuit advantages accrue from the compactness and low impedance connections between elements and electrodes. Such low impedance paths are provided between the screen grid elements, between the two screen grid sections of the duplex tetrode and between the screen grid structure and the cathode. Of equal importance in ultra high frequency amplifiers is the very short length of neutralizer elements which is permitted with the type of screen grid structure described. All of these features combine to provide electrical stability in an ultra high frequency duplex tetrode amplifier.

The screen grid structures provide precision alignment of the elements which is unaffected by the processing temperatures and normal operating conditions when the proper metals are utilized. The method of mounting elements permits effective cooling by circulating a coolant in a manner to be described.

The anode consists of a metallic multi-channel block in which a coolant can be circulated, the coolant being introduced by means of tubular anode supporting leads. The tubular anode sup-

porting leads are arranged and constructed so as to function as elements of the anode resonant circuit formed by connecting the leads together with a shorting bar.

Referring to the drawings, Figures 10, 11 and 13, two-part anodes 80, 81 and 80' and 81' each comprises the same elements such as the electron receiving portion 80, having a plurality of longitudinally extending fins 82 and 83, the fins being displaced longitudinally to provide a space at alternate ends between the fins and the enclosing ends of the portion 81, which receives the member 80. Apertures 84 are provided through which a coolant may be introduced to circulate through the multi-channel path of the anode. The two parts of the anode may be silver soldered together. To the rear of the part 81 is extended a portion 85 which is provided with collar 86 received within outer tubular member 87 enclosing a pair of telescoped inner tubular members 88, 89. This portion 85 is provided with the passageways 89 and 89' as indicated in Figure 11 for the passage of a cooling medium through the anode. The cooling medium is introduced through the outer tubular member and directed out of the anode through the inner tubular member 88, the cross sectional area of which is smaller than the cross sectional area of the space between the two tubes whereby static pressure of the coolant within the anode may be built up for the purpose of increasing the power dissipation of the anode with a given coolant flow.

Since the lead duct of greatest hydraulic impedance is utilized as the coolant exhaust duct, a greater static pressure is obtained in the anode channels with a fixed supply pressure. This greater static pressure permits a higher temperature of the metallic anode block and consequently a greater power dissipation before excessive steam bubbles are formed.

The anode, comprising the portions 80 and 81, is positioned on the opposite side of the mount assembly from anode 80', 81' and has like parts indicated by like primed numbers. Each of these anodes is separately supported and insulated from the other by the tubular members in a manner to be described.

The anode structures and the arrangement of the cooling ducts described provide an average electron bombardment power input per unit area of bombarded surface in excess of 800 watts per square centimeter with a reasonable water flow and pressures not in excess of 70 pounds per square inch. Slip joints are used in the center cooling pipe as shown, which prevents deformation of the lead tube and seal during baking and processing.

The envelope and header assembly to be described and made according to my invention provides a method and means of mounting vacuum tube parts to a plate or other rigid member which is part of the vacuum enclosure and adjustable with respect to the remainder of the vacuum envelope and electrodes affixed thereto.

Referring to Figure 10 the header member or plate 90 is provided with certain apertures and leads extending therethrough and to be described. The header member 90 is provided with a supporting block 91 affixed thereto to which the cathode and screen grid assembly are bolted by means of bolts 92. Thus the screen and cathode are supported directly by the header plate 90. The envelope comprises collar-shaped member 93 provided with flange 94 and a cup-shaped

enclosure 95 which completes the envelope. The header is secured to the flange 94 by means of the bolts 92, and gasket member 96 is utilized for securing a vacuum-tight seal. The spacing ring or gasket 100 is introduced to prevent warping of the header plate when bolted. The adjustment of the header plate with respect to the dome assembly is provided by means of the holes in the header plate, which are machined oversize and permit lateral movement of the bolt and dome assembly with respect to the header plate. An exhaust tube 128 is provided for exhausting the envelope.

The adjustable header method of tube construction and assembly according to my invention provides a practical method for the construction of evacuated devices requiring closely spaced elements. A duplex tetrode is such a device. The cathode, control grids and screen grids may be conveniently assembled, aligned and spaced with the header plate removed from the envelope. The described methods of joining the header plate to the envelope provide adjustment which permits an accurate balance in spacing and capacitance between the anodes and screen grids of the two tetrode sections.

When the vacuum vessel is assembled as described the resulting convenient disassembly makes practical the repair of a damaged device and increases its salvage value.

The combined support and cooling leads for the electrodes and seals form an essential part of a device made according to my invention. Referring to Figures 8, 9, 10, 11 and 12, the cathode blocks 39 and 40 are provided with passages in which the cooling pipes 101 and 102 may be inserted. The ends of tube 101 extend through and are sealed in the header plate 90 as shown in Figure 12. The ends of the cooling pipe 102 extend through an aperture in the header plate and through the plug 103 to which the pipe is hermetically sealed and through which the ends pass. The plug 103 is sealed in the lower end of tubular member 104 surrounded by tubular member 105 sealed in turn to the header. A seal 106, preferably of glass, is made between the two tubular members. These pipes 101 and 102 serve not only to convey the coolant to and from the cathode blocks but also as the leads for supplying the cathode current. It is obvious that the blocks could be drilled to provide a passageway therethrough and tubular leads soldered to the block to communicate with these passageways.

The screen grid assembly is likewise liquid cooled and as shown in Figure 8 each U-shaped member is provided with a U-shaped passageway, such as 110, extending therethrough. As best shown in Figures 8, 9 and 12, a pair of tubular conductors 112 and 113 communicate with the passageways in the U-shaped screen grid elements and are joined together by the coupling tubular member 114. These tubular members extend through and are sealed in the plug 115 supported by tubular member 116 coaxial with the tubular member 117 sealed to the header block 90. An insulating and hermetic seal 118 is made between the tubular members. These cooling pipes and leads also provide the leads for applying the positive voltage to the screen grid electrode.

As shown in Figures 8, 9 and 12, the control grids are each separately supported by the hollow conductors 57 and 57' passing through the collar 120 to which is sealed dome shaped insulating member 121 through which and to which

the tubular members 57 and 57' are sealed with a vacuumtight seal. The inner and outer pipes 56, 57 and 56' and 57' communicate with the tubular extensions 122, 123, 122' and 123' into which and out of which a coolant may be circulated to maintain the grid cool.

The anode is supported from the insulating dome shaped portion of the envelope and sealed to this portion as shown in Figures 8, 10 and 12, a seal being made at 125 and 126 for supporting the anodes in proper spaced relationship with respect to the other electrodes within the tube.

A skirt-shaped shield 127 connected to the screen electrode extends between the screen electrode and the header and completely shields the control grids and control grid leads from the anodes and the anode leads.

As a result of my invention I provide a duplex tetrode arranged with a unitary cathode and focusing structure electrically grounded to a metal envelope, a unitary screen grid electrically by-passed to the grounded cathode by means of a capacitance included in the vacuum chamber and functioning as the screen grid support, two separate and independent control grids with attached neutralizer elements, and anodes supported from the opposite end of the envelope from the other electrodes. When push-pull operation is employed, the two anode leads function with the anodes, as the elements of the anode resonant circuit formed by applying a shorting bar directly to these leads. All of the electrodes, except the anodes, are mounted on a header adjustable with respect to the other member of the vacuum retaining envelope on which the anodes are mounted. The final vacuum closure is by means of a compression gasket.

As a result of my invention I obtain a number of advances and advantages both circuitwise and electronically over conventional push-pull amplifiers. Among these advantages are:

- (a) Low impedance from screen grid to screen grid with attendant small radio frequency potential difference;
- (b) Low impedance between cathodes of the two tetrode sections obtained by means of a common cathode of small dimensions;
- (c) Low impedance between screen grid assembly and a grounded cathode obtained by means of reduced dimensions and a shunting capacitance between screen grid and cathode included within the vacuum envelope;
- (d) Effective liquid cooling of all electrodes with small dimensions and compact structures;
- (e) A better balanced push-pull amplifier because the two tetrode sections may be balanced with respect to each other with greater precision in manufacture than if two individual tetrodes were used; and finally
- (f) Direct capacity neutralization from anodes to control grids for push-pull amplifier application by means of elements of a very short length.
- (g) Effective control of electron beams of large density with small control grid and screen grid currents.
- (h) Reduction of electron transit time at high frequencies by means of electrode configurations which permit the utilization of electron beams of large density together with small effective electrode spacings.
- (i) Increase in band width by means of electrode configurations which provide controlled electron beams of large density and

permit large power dissipation per unit area at the collecting electrodes.

By means of my invention I have been able to provide an internally neutralized high frequency amplifier capable of a power output and at a frequency considerably in excess of conventional amplifier tubes. In one example of my invention, operating as a push-pull amplifier the device delivered a continuous output of 5000 watts at 300 megacycles with a band width in excess of 10 megacycles and a power gain of 10. This device can be operated at frequencies up to 600 megacycles. The average grid current is sufficiently small to permit successful operation as a grid modulated television amplifier at 300 megacycles. By means of the cathode and grid structures employed, cathode electron densities of 3.5 amperes per square centimeter are successfully controlled with control grid currents less than five percent of the anode current. Complete electrical stability and freedom from oscillation has been obtained when the tube is used as a push-pull amplifier.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having an envelope containing a cathode means including a plurality of parallel elongated emitting elements lying in a plane for supplying a plurality of electron beams along parallel space paths, a control electrode next adjacent said emitting elements and having a plurality of flat elongated elements extending transversely of and between said paths and having the flat sides lying in a common plane close to said emitting elements and transversely to said electron paths, the elements of said control electrode lying parallel to said emitting elements, no part of said control electrode lying in the paths of said electrons, a screen electrode having a plurality of spaced elements lying parallel to and registering with said control electrode elements and lying between said beam paths, no part of said elements of said screen electrode lying in the path of said electrons and an electrode for receiving electrons from said cathode means, said cathode means and said other electrodes being closely spaced.

2. An electron discharge device having an envelope containing a cathode assembly for providing a plurality of parallel electron beams along space paths and comprising a planar focusing structure having a plurality of parallel slots in the surface thereof, and a cathode comprising a plurality of parallel elongated emitting elements lying in said slots but out of contact with the surfaces of said focusing structure defining said slots for providing a plurality of electron beams along said space paths, a control electrode next adjacent said emitting elements and having a plurality of flat elongated elements extending transversely of and between said space paths and having flat sides thereof lying in a common plane close to the surface of said focusing structure intermediate said slots, a screen electrode having a plurality of spaced elements lying parallel to and

registering with said control electrode elements and lying between said space paths and electrodes for receiving electrons from said cathode, said cathode and said other electrode being closely spaced.

3. An electron discharge device having an envelope containing a cathode assembly for providing a plurality of parallel electron beams along space paths and comprising a planar focusing structure having a plurality of parallel slots in the surface thereof, and a cathode comprising a plurality of parallel elongated emitting elements lying in said slots but out of contact with the surfaces of said focusing structure defining said slots for providing a plurality of electron beams along said space paths, a control electrode having a plurality of flat elongated elements extending transversely of and between said space paths and having flat sides thereof lying in a common plane close to the surface of said focusing structure intermediate said slots, a screen electrode having a plurality of spaced elements lying parallel to and registering with said control electrode elements and lying between said space paths and an electrode for receiving electrons from said cathode, said cathode and said other electrodes being closely spaced, the surfaces of said planar focusing structure between said slots having a concave transverse cross section.

4. An electron discharge device having an envelope containing a cathode assembly for providing a plurality of parallel electron beams along space paths and comprising a planar focusing structure having a plurality of parallel slots in the surface thereof, and a cathode comprising a plurality of parallel elongated flat emitting elements lying in said slots but out of contact with the surfaces of said focusing structure defining said slots for providing a plurality of electron beams along said space paths, a control electrode having a plurality of flat elongated elements extending transversely of and between said space paths and having flat sides thereof lying in a common plane close to the surface of said focusing structure intermediate said slots, a screen electrode having a plurality of spaced elements lying parallel to and registering with said control electrode elements, the elements of said screen electrode having round transverse sections and lying between said space paths and an electrode for receiving electrons from said cathode, said cathode and said other electrodes being closely spaced, the surfaces of said planar focusing structure between said slots having a concave transverse section.

5. A cathode assembly for providing a plurality of oppositely directed electron beams along space paths and comprising a planar focusing structure having on opposite sides thereof parallel slots in the surfaces thereof, a U-shaped cathode structure received within said slots but out of contact with the surfaces of said focusing structure defining said slots, the legs of said U-shaped cathode structure being received in oppositely disposed slots.

6. A cathode assembly for providing a plurality of oppositely directed electron beams and including an electron focusing structure including a pair of registering plate-like elements insulated from each other and having on the outer faces thereof a plurality of longitudinally extending parallel slots, a U-shaped cathode filament assembly comprising a plurality of parallel U-shaped filament-like elements positioned within said slots but out of contact with the surfaces defining said slots,

the legs of each U-shaped filament-like element being received with oppositely disposed slots.

7. A cathode assembly for providing a plurality of oppositely directed electron beams along parallel space paths and comprising a planar focusing structure having on opposite sides thereof parallel slots in the surfaces thereof, a U-shaped cathode structure comprising a plurality of U-shaped elements lying in parallel planes and received within said slots but out of contact with the surfaces of said focusing structure defining said slots, and means for securing the ends of the legs of said cathode structure to opposite sides and adjacent one edge of said focusing structure.

8. A cathode assembly for providing a plurality of oppositely directed electron beams and including an electron focusing structure having a pair of registering plate-like elements insulated from each other and having on the outer faces thereof a plurality of longitudinally extending parallel slots, a U-shaped cathode assembly comprising a plurality of parallel U-shaped flat filament-like elements within said slots, the adjacent free ends of each leg of the U-shaped cathode elements being secured together, the ends of opposite legs being secured to opposite focusing plate-like elements adjacent one edge thereof.

9. A cathode assembly for providing a plurality of oppositely directed electron beams along space paths and comprising a planar focusing structure having on opposite sides thereof parallel slots in the surface thereof, a U-shaped cathode structure received within said slots but out of contact with the surfaces of said focusing structure defining said slots, the opposite sides of said focusing structure being insulated from each other, the ends of the legs of said U-shaped cathode structure being secured to opposite sides of said focusing structure.

10. A cathode assembly for providing a plurality of parallel electron beams along space paths and comprising a planar focusing structure having a plurality of parallel slots in the surface thereof, and a cathode structure comprising a plurality of flat spaced parallel straight filaments received within said slots but out of contact with the surfaces of said planar focusing structure defining said slots, said flat filaments having the flat surfaces lying in a plane extending parallel to the plane of focusing structure and positioned closely adjacent the surface of said focusing structure.

11. A cathode assembly for providing oppositely directed electron beams and having an electron focusing structure including a pair of registering plate-like elements insulated from each other and having on the outer faces thereof longitudinally extending parallel slots, a U-shaped cathode having its legs within said slots, the free ends of the legs of the U-shaped cathode being secured to opposite plate-like elements adjacent one edge thereof, a pair of spaced oppositely disposed cooling and supporting blocks having cooling passageways extending therethrough and providing between said blocks a U-shaped recess along one side thereof, said focusing structure being partially received within said U-shaped slot and secured to said cooling block.

12. A cathode assembly for providing a plurality of oppositely directed electron beams and having an electron focusing structure including a pair of plate-like elements insulated from each other and having on the outer faces thereof a plurality of longitudinally extending parallel slots, a U-shaped cathode assembly comprising a

plurality of parallel U-shaped filament-like elements within said slots, the free ends of the legs being secured to oppositely disposed plate-like elements and adjacent one edge thereof, and a pair of shield members extending from the secured ends of said cathode filaments and toward the closed end of said cathode filaments for shielding a portion of said cathode filaments.

13. A cathode assembly for providing a plurality of oppositely directed electron beams and including an electron focusing structure having a pair of registering plate-like elements insulated from each other and having on the outer faces thereof a plurality of longitudinally extending parallel slots, a U-shaped cathode assembly comprising a plurality of parallel U-shaped flat filament-like elements, the legs of which lie within said slots, the free ends of the legs being secured to opposite plate-like elements adjacent one edge thereof, and a pair of oppositely disposed cooling and supporting blocks having cooling passageways extending therethrough and supporting said focusing structure and said cathode, and an envelope for said cathode and focusing structure and including a metallic header member, said cooling block being secured to said header member.

14. A cathode assembly for providing oppositely directed electron beams and including an electron focusing structure including a pair of plate-like elements insulated from each other and having on the outer faces thereof parallel slots, a U-shaped cathode having its legs within said slots but out of contact with the surface of said focusing structure defining said slots, the free ends of the legs of the U-shaped cathode being secured to opposite plate-like elements adjacent one edge thereof, a pair of oppositely disposed cooling and supporting blocks having cooling passageways extending therethrough and supporting said focusing structure and U-shaped cathode, and an envelope for said cathode and focusing structure and including a metallic header member, said cooling blocks being secured to said header member, and tubular means extending through said header member and communicating with said cooling blocks for circulating a cooling medium through said passageways.

15. A control grid electrode comprising a hollow tubular member closed at one end and a plurality of spaced conductors extending transversely of and each separately secured at one end to said tubular member and lying parallel to each other and in the same plane, and a second tubular member of smaller transverse section than said first tubular member extending within said first tubular member for providing a cooling medium for said hollow tubular member and said conductors.

16. A control grid electrode comprising a hollow tubular member closed at one end and a plurality of spaced flat conductors each separately secured to said tubular member at one end and lying parallel to each other and in the same plane, and a second tubular member of smaller transverse section than said first tubular member extending within said first tubular member for providing a cooling medium for said hollow tubular member, said hollow tubular member having a stud extending therefrom in a plane transverse to the longitudinal axis of said hollow tubular member, and a flat conducting member secured to the free end of said stud for providing a neutralizing condenser.

17. A unitary electrode structure comprising a

pair of oppositely disposed U-shaped members lying in parallel planes, a plurality of parallel spaced conducting rod-like elements supported on the legs of each of said U-shaped members, and lying in a plane parallel to the plane of the U-shaped member, and end members extending between said oppositely disposed U-shaped members for maintaining said U-shaped members in rigid spaced relationship.

18. A unitary electrode structure comprising a pair of oppositely disposed U-shaped members lying in parallel planes, a plurality of spaced conducting rod-like elements extending parallel to each other from each of the legs of each of said U-shaped members, the rod-like elements supported by each U-shaped member lying in a plane parallel to the plane of the U-shaped member, the rod-like elements on each leg of a U-shaped member extending toward but out of contact with the rod-like elements on the other leg, and end members extending between said oppositely disposed U-shaped members for maintaining said U-shaped members in rigid spaced relationship.

19. An electrode structure comprising a U-shaped member, a plurality of spaced conducting rod-like elements extending parallel to each other from each of the legs of said U-shaped member, said rod-like elements lying in a plane parallel to the plane of the U-shaped member, the rod-like element on each leg extending toward but out of contact with a registering rod-like element on the other leg.

20. An electrode structure comprising a U-shaped member of substantial thickness and having comparatively wide legs, the inner edges of each being provided with offset portions extending from one side of said U-shaped member, a plurality of spaced parallel conducting rod-like elements extending from each of the offset portions and inwardly of the legs of the U-shaped member, said rod-like elements lying in a plane parallel to the plane of the U-shaped member, said rods extending toward but out of contact with each other.

21. A box-like unitary electrode structure comprising a pair of oppositely disposed U-shaped members of substantial thickness and having comparatively wide legs, the inner edges of which are provided with inwardly extending offset portions, a plurality of spaced parallel conducting rod-like elements extending from each of the offset portions of each U-shaped member, and inwardly of the legs of the U-shaped members, said rod-like elements of each U-shaped member lying in a plane parallel to the plane of the U-shaped member, and end members coextensive with the legs of the U-shaped members extending between said oppositely disposed U-shaped members for maintaining said U-shaped members in rigid spaced relationship.

22. A unitary electrode structure comprising a pair of oppositely disposed U-shaped members of substantial thickness and lying in parallel planes, a plurality of spaced parallel conducting rod-like elements supported by the legs of each of said U-shaped members, the rod-like elements supported by each U-shaped member lying in a plane parallel to the plane of the U-shaped member, and end members extending between said oppositely disposed U-shaped members for maintaining said U-shaped members in rigid spaced relationship, said U-shaped members having passageways therethrough for permitting circulation of a cooling medium.

23. A unitary electrode structure comprising a pair of oppositely disposed U-shaped members of substantial thickness and lying in parallel planes, a plurality of spaced parallel conducting rod-like elements supported by the legs of each of said U-shaped members, the rod-like elements supported by each U-shaped member lying in a plane parallel to the plane of the U-shaped member, and end members extending between said oppositely disposed U-shaped members for maintaining said U-shaped members in rigid spaced relationship, said U-shaped members having passageways therethrough for permitting circulation of a cooling medium, and tubular conducting means for said cooling medium communicating with said passageways.

24. In an electron discharge device, a cathode and screen grid electrode assembly including cathode assembly for providing a plurality of oppositely directed electron beams along parallel space paths and comprising a planar focusing structure having on opposite sides thereof parallel slots in the surfaces thereof, a U-shaped cathode structure comprising a plurality of U-shaped elements lying in parallel planes received within said slots but out of contact with the surfaces of said focusing structure defining said slots, and a box-like screen grid electrode surrounding said cathode and focusing structure and having electron permeable sides registering with the legs of said cathode, said box-like screen grid electrode being insulatingly secured to said cathode assembly.

25. In an electron discharge device, a cathode and screen grid electrode assembly including cathode assembly for providing a plurality of oppositely directed electron beams along space paths and including an electron focusing structure including a pair of registering plate-like elements insulated from each other and having on the outer faces thereof a plurality of longitudinally extending parallel slots, a U-shaped cathode filament assembly comprising a plurality of parallel U-shaped filament-like elements within said slots, and a screen electrode surrounding said cathode and focusing electrode and comprising a unitary box-like structure having open sides, rod-like elements supported on said box-like structure and extending across said open sides and registering with the space between said space paths, and being insulatingly secured to said cathode assembly.

26. An anode electrode for an electron discharge device comprising a hollow member having a single continuous multi-channel passage extending therethrough providing a back and forth passage, a tubular member connected to and supporting said anode, one end of said multi-channel passageway communicating with said tubular member and another tubular member within said first tubular member and communicating with the other end of said multi-channel passageway.

27. An anode electrode for an electron discharge device comprising a hollow member having a plurality of parallel ribs within said member, alternate ribs being offset longitudinally with respect to each other to form a single continuous multi-channel passage extending therethrough, a tubular member connected to and supporting said anode, one end of said multi-channel passageway communicating with said tubular member, and tubular means within said first tubular member and communicating with the other end of said multi-channel passageway, said inner tubular means comprising a pair of members telescoped over one another.

28. An anode electrode for an electron discharge device comprising a flat plate-like conducting element having one surface for receiving electrons and having on the opposite surface thereof a plurality of parallel ribs, alternate ribs being offset longitudinally with respect to each other, and a cooperating member of U-shape for receiving said ribs, the inside surface of said U-shaped member and said ribs providing a tortuous continuous channel for the passage of a cooling medium, said U-shaped member having a chamber and passageways extending from said chamber to opposite sides of said tortuous channel for circulating a cooling medium therethrough.

29. An anode electrode for an electron discharge device comprising a hollow box-like member, a plurality of parallel ribs within said box-like member, alternate ribs being offset longitudinally with respect to each other for providing passageways between the ends of said ribs and the inside walls of said box-like member, whereby a continuous multi-channel passageway is provided through said box-like member, the walls of said box-like member having passageways extending therethrough and communicating with opposite ends of said multi-channel passageway.

30. An anode electrode for an electron discharge device comprising a hollow box-like member, a plurality of parallel ribs within said box-like member, alternate ribs being offset longitudinally with respect to each other for providing passageways between the ends of said ribs and the inside walls of said box-like member, whereby a continuous multi-channel passageway is provided through said box-like member, said box-like member having an offset portion provided with a chamber and passageways extending from said chamber to opposite ends of said multi-channel passageway.

31. An electron discharge device having an envelope including a conducting header member, a cathode assembly and a screen electrode insulated from said cathode assembly, said cathode assembly and screen electrode being supported from said header member, said header member having a plurality of apertures therethrough, and a plurality of leads extending from said cathode assembly through said header member, and a lead extending from said screen electrode and through an aperture and insulatingly sealed therein, and a control electrode positioned between said cathode assembly and screen electrode and having a lead insulatingly supporting said control electrode from said header member and extending through another of said apertures and sealed therein, and a closure member for said header member providing an envelope, an anode, a lead extending through said closure member and supporting said anode adjacent said screen electrode, said cathode assembly, said control and screen electrodes and said anode all having passageways extending therethrough through which a cooling medium may be circulated, said leads comprising tubular members into which and out of which a cooling medium may be circulated into and out of said cathode assembly, control and screen electrodes and said anode.

32. An electrode assembly for providing a plurality of oppositely directed electron beams and including an electron focusing structure having a pair of registering plate-like elements insulated from each other and having on the outer faces thereof a plurality of longitudinally extending parallel slots, a U-shaped cathode assembly com-

prising a plurality of parallel U-shaped filament-like elements, the legs of which lie within said slots, the free ends of the legs being secured to opposite plate-like elements adjacent one edge thereof, a pair of oppositely disposed cooling and supporting blocks having cooling passageways extending therethrough and supporting said focusing structure and said cathode, and an envelope for said cathode and focusing structure and including a metallic header member, said cooling blocks being secured to said header member, and a screen electrode comprising a unitary box-like structure having sides through which the electron paths lie, said box-like screen electrode surrounding said cathode and focusing electrode and insulatingly secured to said cooling blocks, control electrode means between said cathode and said screen electrode, and anode means adjacent the sides of said screen electrode.

33. An electron discharge device having an envelope closed by a metal header, a flat cathode within said envelope, a control grid electrode positioned at each side of said cathode, each grid electrode comprising a hollow tubular member closed at one end and a plurality of spaced flat conductors secured to said tubular member near the closed end and lying parallel to each other and in the same plane, and a second tubular member having a smaller cross section and extending within said first tubular member for providing a cooling medium for said hollow tubular member, said hollow tubular member having an L-shaped lug extending therefrom in a plane transverse to the longitudinal axis of said tubular member, and a flat conducting plate secured to the end of said L-shaped lug for providing a neutralizing condenser, said header member having an aperture extending therethrough, the hollow tubular members of said control grid electrodes extending through and insulatingly sealed in said aperture, and an anode electrode positioned adjacent each control grid electrode on the side of the control grid electrode away from said cathode, the plate on each control grid electrode extending toward but out of contact with the anode on the other side of the cathode.

34. An electron discharge device having an envelope closed by a metal header, a flat cathode on said header, a control grid electrode positioned at each side of said cathode and comprising a hollow tubular member closed at one end and a plurality of spaced flat conductors each secured separately to said tubular member near the closed end and lying parallel to each other and in the same plane, and a second tubular member having a smaller cross section and extending within said first tubular member for providing a cooling medium for said hollow tubular member, said header member having an aperture extending therethrough, the hollow tubular members of said grids extending through and insulatingly sealed in said aperture, and an anode electrode positioned adjacent each grid on the side of the grid away from said cathode, and leads extending through said envelope and supporting said anode electrodes.

35. An electron discharge device having an envelope containing a cathode assembly for providing a plurality of electron beams along spaced paths and comprising a focusing structure hav-

ing a plurality of parallel slots in the surface thereof, and a cathode comprising a plurality of parallel elongated emitting elements lying in said slots but out of contact with the surfaces of said focusing structure defining said slots for providing a plurality of electron beams along said space paths, a control electrode next adjacent said emitting elements and having a plurality of elongated elements extending transversely of and between said space paths and having surfaces thereof lying equidistant from and close to the surface of said focusing structure intermediate said slots, and an electrode for receiving electrons from said cathode, said cathode and said other electrodes being closely spaced.

36. An electron discharge device having an envelope containing a cathode assembly for providing a plurality of electron beams along space paths and comprising a focusing structure having a plurality of parallel slots in the surface thereof, and a cathode comprising a plurality of elongated emitting elements lying in said slots but out of contact with the surfaces of said focusing structure defining said slots for providing a plurality of electron beams along said space paths, a control electrode next adjacent said emitting elements and having a plurality of elongated elements extending transversely of and between said space paths and having flat surfaces thereof lying close to the surface of said focusing structure intermediate said slots, and an electrode for receiving electrons from said cathode, said cathode and said other electrodes being closely spaced.

37. An electron discharge device having an envelope containing a cathode assembly for providing a plurality of parallel electron beams along space paths and comprising a focusing structure having a plurality of parallel slots in the surface thereof, and a cathode comprising a plurality of elongated emitting elements lying in said slots but out of contact with the surfaces of said focusing structure defining said slots for providing a plurality of electron beams along said space paths, a control electrode next adjacent said emitting elements and having a plurality of elongated elements extending transversely of and between said space paths and each of said elements having at least one flat side lying close to the surface of said focusing structure intermediate said slots and an electrode for receiving electrons from said cathode, said cathode and said other electrodes being closely spaced.
